DESIGN FOR A COSTUMER

George H. Amt, Indianapolis, Ind.

Application August 27, 1945, Serial No. 121,667

Term of patent 14 years

(Cl. D33—8)

To all whom it may concern:

Be it known that I, George H. Amt, a citizen of the United States, and a resident of Indianapolis, in the county of Marion and State of Indiana, have invented a new, original, and ornamental Design for a Costumer, of which the following is a specification, reference being had to the accompanying drawing forming a part thereof, and in which:

Fig. 1 is a perspective view of a costumer, showing my new design;

Fig. 2 is a top plan view of the same;

Fig. 3 is a side elevational view of the same;

Fig. 4 is a side elevational view of the same showing the hinged members folded up against the side of the costumer and the blocks below the hinged members pivoted to vertical position.

I claim:

The ornamental design for a costumer, as shown and described.

GEORGE H. AMT.
